[57] ABSTRACT

A neck assembly for a container body such as may be formed from polymers of the unsaturated olefin series in a blow molding operation. The container body has a flexible annular neck extending therefrom, and is of a thickness that can be folded upon itself about an annular ring. A neck piece has an annular groove therein of a diameter corresponding to the diameter of the annular ring and the folded over portions of the annular neck together with the annular ring are inserted into the annular groove with an interference fit.

The annular groove is undercut to cooperate with a land on the annular ring to provide a tightly locking assembly.

NECK ASSEMBLY FOR THIN WALLED CONTAINER

The structure disclosed herein constitutes an improvement over that shown in Winstead U.S. Pat. No. 3,124,282.

It is a principal object of this invention to provide a neck assembly which can be secured to the flexible and compliant annular neck opening of a container body.

Another object is to provide a neck assembly for a container body having an annular neck opening capable of being folded about an annular ring and then inserted into a complementary neck piece to complete the neck assembly.

DRAWING

FIG. 1 is a longitudinal sectional view taken through a neck assembly for a container body, the neck assembly being constructed in accordance with the present invention.

FIG. 2 is a sectional view through the compliant annular neck of the container showing one of the steps of folding the neck about an annular ring forming a part of the neck assembly according to the invention; and

FIG. 3 is a view similar to FIG. 2 showing the completed steps of folding the compliant annular neck about the annular ring.

Referring now to the drawing, the neck assembly according to the present invention is denoted by the reference numeral 10 and is shown in the environment of a container body 11 having an annular neck 12. The container body 11 and the annular neck 12 are integrally formed and may be formed in a blow molding process using resins or polymers of the unsaturated olefin series. The annular neck 12 is compliant and is folded in the steps seen in FIGS. 2 and 3 about an annular ring 13 having a land or stiffening bead 14, giving a generally key-hole shaped cross-section.

The compliant annular neck 12 is folded about the ring 13 in the form of a connected pair of folds 15 with ring 13 therebetween.

A neck piece 16 is adapted to be joined to the annular ring

13 with the folds 15 therearound, and has a flange 17 and an annular rib 18 molded integrally as a unit. The neck piece 16 has a passage 21 which is coaxial with the annular flange 12 of the container body 11.

5 Neck piece 16 has an annular groove 19 with entrant jaws 20 thereto, the annular groove 19 having a diameter corresponding to the diameter of the annular ring 13. The groove 19 is undercut as at 22 so that the land 14 of the ring 13 together with the folds 15 thereabout may be inserted into the annular groove 19, the annular ring 13 being locked to the neck piece 16 by reason of the undercutting described.

The neck piece 16 has male threads 23 moulded integrally therewith, these threads cooperating with female threads 26 of a closure cap 24.

I claim:

1. A neck assembly for attaching a pliant container neck to a rigid cap, consisting solely of:
  - a. a retainer ring having a generally key-hole shaped cross-section with a circular upper portion and an elongated lower portion;
  - b. a neck piece including:
    - i. a neck portion for attachment to said cap;
    - ii. a body portion for attachment to said container neck and having a groove of a cross-section similar to the cross-section of said ring for receiving said ring;
  - c. said groove having a circular upper portion and an elongated lower portion communicating therewith, said lower portion being defined by opposed flexible entrant jaws;
  - d. said container neck having a portion thereof folded over said ring and positioned within said groove with the upper portion of said groove embracing the upper portion of said ring and said container neck and with said entrant jaws snugly engaging the lower portion of said ring and said container neck to provide a self-contained, interlocking connection between said neck piece and said container neck.
